UNITED STATES PATENT OFFICE.

JOHN ZIPP, OF CHATTANOOGA, TENNESSEE, ASSIGNOR TO THE CAHILL IRON WORKS, A CORPORATION OF TENNESSEE.

DESIGN FOR A WASHBASIN.

No. 37,957.

Specification for Design.

Patented April 17, 1906.

Application filed February 26, 1906. Serial No. 303,125. Term of patent 7 years.

To all whom it may concern:

Be it known that I, JOHN ZIPP, a citizen of the United States, residing at Chattanooga, in the county of Hamilton and State of Tennessee, have invented a new, original, and ornamental Design for Washbasins, reference being had to the accompanying drawing.

In said drawing the figure is a perspective of a washbasin embodying my new and ornamental design.

I claim—

The ornamental design for a washbasin, as shown.

JOHN ZIPP.
